Primary Examiner — Paula Allen Greene*(74) Attorney, Agent, or Firm* — Faegre Drinker Biddle & Reath LLP**(57) CLAIM**

The ornamental design for an ear cup, as shown and described.

DESCRIPTION

FIG. 1 is an isometric perspective view of an ear cup, illustrating our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines illustrate a portion of the ear cup that forms no part of the claimed design.
